UNITED STATES PATENT OFFICE.

WILLIAM J. REGAN, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

UNCOUPLING MECHANISM.

1,417,567.

Specification of Letters Patent. Patented May 30, 1922.

Application filed October 6, 1921. Serial No. 505,684.

To all whom it may concern:

Be it known that I, WILLIAM J. REGAN, a citizen of the United States, residing at Pittsburgh, in the county of Allegheny and State of Pennsylvania, have invented certain new and useful Improvements in Uncoupling Mechanism; and I do hereby declare the following to be a full, clear, and exact description of the invention, such as 10 will enable others skilled in the art to which it appertains to make and use the same.

My invention relates to uncoupling mechanism for operating the lock of a car coupler. While it is especially designed to 15 provide uncoupling means particularly applicable to the Master Car Builders' D-type coupler employing a bottom operated lock, the invention may be embodied in uncoupling mechanism applicable to other 20 forms of couplers as well.

The primary object of the invention is to afford an easily operated uncoupling mechanism which consists of a few simple parts compactly arranged so as to enable the device to be capable of being applied in a 25 space of comparatively small vertical dimension.

The principal feature of the invention, generally stated, consists in moving the lock 30 of the coupler by means of a rotatable member operatively connected to the lock and slidably supported near its rear end by an actuating member that is pivotally connected at a point below the said rotatable member to 35 a movable support adapted to swing lengthwise of the car.

A further feature of the invention consists in moving the lock of a coupler to unlocked positions by means of a rotatable member 40 operatively connected to the lock and which slidably engages an actuating member that is pivotally connected to the lower end of an inverted bail whose upper end is provided with a plurality of hooks whereby the bail 45 may be swingingly and detachably supported by the coupler carrier iron.

As will hereinafter appear, there are further features of the invention residing in particular details of construction and in 50 special combinations of parts.

In the drawings illustrating the preferred embodiment of the invention—

Figure 1 is a view, partly in side elevation and partly in section, of an uncoupling 55 mechanism embodying the invention, the car

coupler illustrated being of the well known Master Car Builders' D-type.

Figure 2 is a view, partly in side elevation and partly in vertical section, of a portion of the construction shown in Fig. 1, the carrier iron device being omitted and the parts being in the positions they occupy when the coupler lock has performed an extended unlocking movement.

Figure 3 is a detail view of a portion of the mechanism, partly in vertical section and partly in rear elevation, portions of the uncoupling levers being broken away.

Figure 4 is a section on the line 4—4, Fig. 3, the forward end of the vertically rotatable bar being broken away.

Figure 5 is a sectional view on the line 5—5, Fig. 3, portions of the uncoupling levers being broken away.

Figure 6 is a detail plan view of a slotted member designed to be secured to the coupler carrier iron device to enable the uncoupling mechanism to be supported therefrom.

Figure 7 is a section on the line 7—7, Fig. 1, parts of the mechanism being broken away.

In the drawings, 1 indicates a car coupler of the Master Car Builders' D-type. The lower end of its lock 2 is movably connected to a link 3 which projects downwardly through the coupler head and is pivoted at its lower end to a swinging lift lever 4 which is itself pivotally secured to the under side of the coupler head. The link 3 and pivoted lift lever 4 may, as shown, accord in form, arrangement and mode of operation with the standard parts of the bottom lift devices of the D-type coupler.

When the coupler is designed to be capable of a wide range of lateral swinging movement its shank may be provided near its rear end with a pivot pin opening 5 for receiving a tail pin (not shown) by which the coupler may be pivotally connected to the draft rigging in the usual manner. The form of coupler carrier iron device illustrated in the drawings and designated generally by the numeral 6, will be recognized as a style now applied to Pullman cars and provided with centering mechanism for normally maintaining the coupler in the longitudinal axis of the car. While the invention is illustrated in conjunction with this particular form of carrier iron, with which it is well adapted to be used, it is to be understood

that the invention is not limited to the structural features of the carrier iron employed.

The swinging lift lever 4 is operated to effect an unlocking movement of the lock 2 by means of a vertically rotatable member 7 which is preferably interlockingly connected to the lift lever by a hook and eye connection, the member 7 having a hooked forward end 8 which cooperates with an aperture 9 with which the lift lever is provided at its inner end. The member 7, which is preferably formed as a simple bar, is slidably supported rearwardly of the coupler lock 2 by a member 10 which, upon being actuated, is adapted to cause the bar 7 to perform a vertical rotation resulting in an unlocking movement of the coupler lock. The actuating member 10 is pivotally supported at a point below the rotatable bar 7 on the lower part of an inverted bail or U-shaped member 11 whose upper end is provided with a plurality of spaced hooks 12 affording means for effecting a pivotal connection with the carrier iron allowing said bail to swing lengthwise of the car. In the construction shown in the drawings the carrier iron device 6 is illustrated as having riveted thereto a bracket member 13 provided with a transversely elongated slot 14 for detachably receiving the hooks 12 of the swinging bail. The pivotal connection between the actuating member 10 and the swinging bail 11 is preferably effected by providing the lower end of said actuating member with a hook or bearing projection 15 whose downwardly opening recess receives the lower end of the bail 11.

The actuating member is formed with an upwardly opening recess 16 permitting the bail 11 to enter and pivotally engage said member 10 below the vertically rotatable bar 7. The recess 16 also receives the downwardly extending inner ends 17 of rotatable uncoupling levers 18 which extend toward the sides of the car in the usual manner, the bounding side walls 19 of the actuating member 10 being provided above the point of pivotal connection of said actuating member to said bail with apertures 20 permitting the introduction of the bent ends 17 of the uncoupling levers and forming journal bearings for said levers 18. Except that it is preferred to extend the bent inner ends 17 of the uncoupling levers downwardly instead of upwardly, said levers may be of the well known form illustrated in the I. H. Milliken Patent No. 1,184,116, dated May 23, 1916.

The actuating member 10 is provided with a forward wall 21 adapted to be engaged by the bent ends 17 of the uncoupling levers to effect a lock actuating rotation of the member 10 when either of the independently rotatable uncoupling levers is operated by the trainman to cause an unlocking movement

of the coupler lock. Connecting the side walls 19 of the actuating member and passing over the rotatable uncoupling bar 7 to the rear of the uncoupling levers 18, is a transversely extending lug portion 22 adapted to engage the rotatable bar 7 when the mechanism performs an unlocking operation, the rotation of the actuating member 10 induced by the movement of either of the uncoupling levers 18 thereby being communicated to the member 7 through the engagement therewith of the transversely extending portion 22 and the upper end of the front wall 21 of the actuating member 10.

The rotatable member 7 may be caused to perform an unlocking operation by manipulating either of the uncoupling levers 18. When either of said levers is rotated in the proper direction its bent inner end 17 presses against the forward wall 21 of the swinging actuating member 10, causing the latter to rotate upon the supporting bail 11. This results in bringing the portions 21 and 22 of the actuating member into engagement with opposite sides of the rotatable member 7, thereby compelling the latter to execute an unlocking movement and thus causing the lock lift lever 4 and link 3 to communicate a corresponding movement to the coupler lock 2. During the unlocking rotation of the member 7 and its actuating means 10 the supporting bail 11 swings lengthwise of the car as may be required to permit the forward end of the rotatable member 7 readily to conform to the movement of the lift lever 4.

While the several parts of the mechanism are detachably connected and may therefore be easily assembled and disassembled they are interlocked so that accidental disassociation is prevented when the device is in service.

I claim:

1. In an uncoupling mechanism, the combination with a car coupler and its lock, of means for moving said lock to unlocked position, said means involving a rotatable member operatively connected to said lock and extending rearwardly therefrom, means supportingly engaging and adapted to actuate said rotatable member, and swinging means pivotally connected to said actuating means below said rotatable member.

2. In an uncoupling mechanism, the combination with a car coupler and its lock, of means for moving said lock to unlocked position, said means involving a vertically rotatable member operatively connected to said lock, means supportingly engaging and adapted to actuate said rotatable member, and an inverted bail for pivotally supporting said actuating means.

3. In an uncoupling mechanism, the combination with a car coupler, its lock and carrier iron, of means for moving said lock to

unlocked position, said means involving a rotatable member operatively connected to said lock and extending rearwardly therefrom, means supportingly engaging and adapted to actuate said rotatable member, and a bail swingingly supported by said carrier iron and pivotally supporting said actuating means below said rotatable member.

4. In an uncoupling mechanism, the combination with a car coupler, its lock and carrier iron, of means for moving said lock to unlocked position, said means involving a rotatable member operatively connected to said lock, means supportingly engaging and adapted to actuate said rotatable member, and a bail interposed between said carrier iron and said actuating means and swingingly connecting said actuating means to said carrier iron, said bail being provided with a plurality of hooks adapted to engage one of said members connected by said bail.

5. In an uncoupling mechanism, the combination with a car coupler, its lock and carrier iron, of means for moving said lock to unlocked position, said means involving a rotatable member operatively connected to said lock and extending rearwardly therefrom, means supportingly engaging and adapted to actuate said rotatable member, and a U-shaped member interposed between and having pivotal connection with said carrier iron and said actuating means, said U-shaped member being provided with a plurality of spaced hooks affording means for effecting one of said pivotal connections.

6. In an uncoupling mechanism, the combination with a car coupler, its lock and carrier iron, of means for moving said lock to unlocked position, said means involving a vertically rotatable member operatively connected to said lock and extending rearwardly therefrom, means supportingly engaging and adapted to actuate said rotatable member, and a swinging bail pivotally connected to said carrier iron and to said actuating means, said bail being provided at its upper end with a plurality of spaced hooks whereby it is detachably connected to said carrier iron.

50 7. In an uncoupling mechanism, the combination with a car coupler and its lock, of means for moving said lock to unlocked position, said means involving a rotatable member operatively connected to said lock and extending rearwardly therefrom, means supportingly engaging and adapted to actuate said rotatable member, and a swinging inverted bail movably supporting said actuating means, said actuating means being provided with a downwardly opening recess through which the lower portion of said bail extends.

8. In an uncoupling mechanism, the combination with a car coupler and its lock, of means for moving said lock to unlocked position, said means involving a vertically rotatable member operatively connected to said lock and extending rearwardly therefrom, means engaging and adapted to actuate said rotatable member, and a swinging U-shaped member passing beneath said rotatable member and supporting said actuating means, said actuating means having a rocking bearing on the lower part of said U-shaped member.

9. In an uncoupling mechanism, the combination with a car coupler and its lock, of means for moving said lock to unlocked position, said means involving a rotatable member operatively connected to said lock, a swinging member adapted to actuate said rotatable member, a rotatable uncoupling lever supportingly journaled on and adapted to actuate said swinging member, and swinging means for pivotally supporting said swinging member at a point below the point of support of said uncoupling lever.

10. In an uncoupling mechanism, the combination with a car coupler and its lock, of means for moving said lock to unlocked position, said means involving a vertically rotatable member operatively connected to said lock and extending rearwardly therefrom, a swinging member adapted to actuate said rotatable member, an uncoupling lever engaging and adapted to actuate said swinging member, and a movable bail for pivotally supporting said swinging member, said rotatable member having slidable engagement with said swinging member, said swinging member being provided with a forward wall adapted to be engaged by a portion of said lever to effect a lock actuating rotation of said swinging member when said lever is operated, and said swinging member also having an upwardly opening recess permitting said bail to enter and have pivotal engagement with said swinging member below said rotatable member.

11. In an uncoupling mechanism, the combination with a car coupler, its lock and carrier iron, of means for moving said lock to unlocked position, said means involving a rotatable member operatively connected to said lock and extending rearwardly therefrom, a swinging member slidably supporting and adapted to actuate said rotatable member, and a bail pivotally supporting said swinging member, said bail being provided with a plurality of hooks, and said carrier iron having an elongated slot adapted to receive said hooks.

In testimony whereof I affix my signature.
WILLIAM J. REGAN.
